UNITED STATES PATENT OFFICE.

GUS LEE THOMPSON, OF BUFFALO, NEW YORK.

SPARK PLUG.

Application filed November 26, 1926. Serial No. 150,962.

My invention relates to improvements in spark plugs and the object of the invention is to construct a plug which will produce a double spark under all functioning conditions, and a further object of the invention is to so mount the points in relation to each other and to the interior of the shell that the plug may be readily taken apart for cleaning purposes without bending or distorting the points. A still further object of the invention is to provide a plate which is adapted to receive and discharge the spark and also constitute a baffle for preventing the deposition of carbon within the exposed interior of the plug.

My invention consists of a spark plug constructed and arranged all as hereinafter more particularly described and illustrated in the accompanying drawing, in which:

Fig. 1 is a vertical cross sectional view through my plug.

Fig. 2 is a side elevational view of the plug, and,

Fig. 3 is an inverted plan view thereof.

Like characters of reference indicate corresponding parts in the different views.

The plug shell 1 conforms in appearance to the standard type, being furnished at its upper end with a hexagonal spanner receiving member 2 and at its lower end with an exteriorly threaded portion 3 which is of course adapted to be threaded into the engine cylinder. Inferiorly of the plug shell

1 and intermediately of its length I form a boss 4 of reduced diameter which is adapted to support the porcelain insulator 5 which is inserted into the shell. The insulator is of cylindrical formation having an enlarged ring 6 formed thereon intermediately of its length, the lower end of such ring being adapted to be seated within an enlarged portion 7 in the upper end of the boss 4, so that the outer edge of the lower face of the ring rests upon the shoulder 8 formed between the inner face of the boss 4 and enlarged portion 7. The interior of the upper end of the shell 1 extending downwardly to the upper face of the boss 4 is threaded for the major portion of its depth and adapted to receive a sleeve 9 which is threaded thereto, the interior diameter of the lower end of such sleeve being enlarged and adapted to surround the upper end of the ring 6, the upper edge of such ring being chamfered as is also the shoulder formed by the enlarged lower end 10 of the sleeve 9. The

upper end of such sleeve is of course furnished with a hexagonal spanner receiving portion 11.

12 and 13 are a pair of metal rods embedded within the porcelain 5, the rod 12 projecting through the upper end thereof and being suitably threaded to constitute the usual cable receiving binding post, a thumb nut 14 being threaded thereon, the lower end 60 of such rod projecting below the lower face of the porcelain 5, and adapted to constitute one of the plug points 15. For preventing any possibility of the rod 13 rotating within the porcelain 5 and thus allowing the 65 member 16 to move out of its aligned position I provide a turned-over upper end 19 upon the rod and also a bend 20 intermediately of its length which will positively prevent any rotative movement as the porcelain 70 is molded around the rod.

Upon the lower end of the rod 13, I furnish a circular metal plate 21, such plate being of slightly less diameter than the interior diameter of the boss 4 to permit it 80 passing therethrough and furnished with an orifice 22 into which the lower end of the point 15 projects, the distances between the point 15 and the periphery of the orifice 22 and the periphery of the plate 21 and the 85 point 17 which extends downwardly from the inner face 18 of the spark plug shell being such that spark gaps of correct width are formed.

The operation of my plug under working 90 conditions is as follows:

When the electrical current passes from the cap into the rod 12, it jumps from the point 15 across the gap constituted between such point and the periphery of the orifice 95 22 in the plate 21 and passes from thence across the plate and jumps to gap constituted between the periphery of the plate and the point 17, from where it follows the usual path into the engine block. It will be appreciated that the spark, at all times, when functioning must jump both gaps as the plate 21 constitutes its only passage thru to the engine block. Should one of the gaps 100 become bridged with carbon, the current will, of course, pass therethru, but the spark will occur as long as the other gap remains unbridged. By the provision of the plate 105 21, I have provided a baffle, which will, to quite an extent, prevent the accumulation of 110 carbon deposit within the lower end of the interior of the block shell, and as it is also

of slightly less diameter than the interior diameter of the boss 4 in the shell, the porcelain 5 can be readily removed for cleaning purposes without damage to either the plate 5 or points.

From the foregoing description it will be seen that I have constructed an extremely simple form of spark plug which normally produces a double spark under all working conditions and which will produce a single spark even though one of the gaps become completely bridged with carbon.

What I claim as my invention is:

A spark plug for internal combustion engines comprising a main body portion provided with a bore open at its lower end, a pair of electrodes embedded within the body

of insulating material positioned within the main body portion, one of said electrodes communicating with the spark plug cable, 20 the other electrode being insulated within the body of insulating material, a third electrode depending from the inner wall of the bore of the main body portion, and a plate positioned upon the lower end of the insulated electrode and having an orifice therein into which the electrode communicating with the cable projects, the side of the orifice and the end of said electrode constituting one spark gap, and the side of the plate and the end of the third electrode constituting the other spark gap. 30

GUS LEE THOMPSON.
